SPICE AND CONDIMENTS RACK

John C. Hampe and Harold T. Genge,
Centralia, Wash.

Application July 27, 1948, Serial No. 147,794

Term of patent 7 years

(Cl. D44—29)

To all whom it may concern:

Be it known that we, John C. Hampe and Harold T. Genge, citizens of the United States of America, residing at Centralia, in the county of Lewis and State of Washington, respectively, have invented a new, original, and ornamental Design for a Spice and Condiment Rack, of which the following is a specification, reference being had to the accompanying drawing, forming part thereof.

In the drawing:

We claim:

The ornamental design for a spice and condiment rack, as shown.

JOHN C. HAMPE.
HAROLD T. GENGE.
